US00D904901S

(12) **United States Design Patent** (10) Patent No.: **US D904,901 S**
(45) Date of Patent: **** Dec. 15, 2020**

(54) **CASE WITH EARPHONES**

(71) Applicant: **Apple Inc.**, Cupertino, CA (US)
(72) Inventors: **Vijay Karthik Koneru**, Los Angeles, CA (US); **Christopher Wiita**, West Hollywood, CA (US); **Duy P. Le**, Los Angeles, CA (US); **Robert Boyd**, Los Angeles, CA (US); **Sean Stewart Corbin**, South Lake Tahoe, CA (US); **Guillaume Raoult**, San Francisco, CA (US); **Elvin Chu**, San Francisco, CA (US); **Martin Gschwandtl**, San Francisco, CA (US); **Christopher Kuh**, San Francisco, CA (US); **Robert Brunner**, Glen Ellen, CA (US)

(73) Assignee: **Apple Inc.**, Cupertino, CA (US)

(**) Term: **15 Years**

(21) Appl. No.: **29/685,004**

(22) Filed: **Mar. 25, 2019**

(51) LOC (12) Cl. **09-03**
